Henry B. Olson Inventor:
Wilson & McCanna Atty.

UNITED STATES PATENT OFFICE.

HENRY B. OLSON, OF ROCKFORD, ILLINOIS.

GAUGE FOR SEWING MACHINES.

Application filed June 24, 1925. Serial No. 39,225.

My invention relates to gauges for sewing machines, and more especially to a gauge for attachment to machines for sewing harness, such as horse collars, belts or other 5 similar leather goods.

The invention consists further of an attachment for and combination with a machine for sewing horse collars or other articles, wherein a leather thong is employed 10 as in a thong sewing machine. My invention is not, however, limited to such use, as it may be employed in ordinary thread stitching or sewing operations, but particularly in connection with horse collars.

With machines as heretofore constructed it was necessary to sew the plies of a horse collar body together near the edges, at the 15 rear edge or back of the collar with a whipping-up stitch at a narrow space or margin 20 from the near edge, and at the front at a similar margin from the front edge of the body. The rim is then sewed to the body by means of a leather thong making a "pop" 25 stitch, as by machines well known in the art as "thong sewing machines" as shown, for example, in the patent to Gnoeth, 1,193,460 dated August 1, 1916.

The sewing or stitching at the front is known as a middle seam owing to the middle 30 seaming of the rim of the collar to the body by means of a thong, for which the thread stitching serves as a guide within which the awl punches and the thonging is done in the middle seaming operation on 35 the machines referred to. Such middle seaming with a thong has been either done by hand where the collars or plies are thick, such as at the throat portion, with slow 40 production, or it has been difficult to keep within the thread seam so as not to overrun it and at the same time maintain a uniform and proper even overlap between the body and the rim over the body of the collar. The machines could not accommodate 45 the thickness at the throat portion owing to the presser foot and awl carrier moving too close to the bed plate or table, and it has been impractical if not impossible to sew the rim to the body of a horse collar without 50 the preliminary stitching because there was no means of guiding the edges or guiding the overlap of the rim and body, especially since the rim fits over the body and conceals or precludes the edges of the body from view during the sewing operation. 55 Thus the thread stitches were necessary as

a guide to the overlap and thong stitching. The present invention is designed in connection with the machine to gauge the overlap and render the preliminary thread stitching unnecessary by maintaining the proper and uniform overlap of the rim with respect to the body, thus making it possible to sew the rim directly and in the first instance to the body with a thong and with proper overlap of the rim on the body. This eliminates the thread stitching operation and cost thereof and permits the collars to be sewed more quickly and economically, so that cost of manufacture is greatly reduced and production increased from seven to ten fold.

The invention further comprehends and has for its object, the provision of a gauge, especially for thong sewing machines for horse collars, which comprises a simple and novel structure capable of convenient, practical, and economical manufacture, and application easily to the work tables of sewing machines, especially of the type referred to. Furthermore, the gauge will readily accommodate the parts, such as collar body and rim, to be sewed together and effectively and evenly guides the edges of the parts up to a maximum thickness. It also prevents too little or excessive overlap as will be herein-after more fully set forth.

The invention further consists of certain novel combinations and arrangements of parts to be hereinafter more fully described.

Other objects and attendant advantages will be appreciated by those skilled in this art as the invention becomes better understood by reference to the following description when considered in connection with the accompanying drawings, in which—

Figure 1, is a fragmentary side or front elevation illustrating a type of sewing machine to which the invention may be applied;

Fig. 2 is an enlarged fragmentary side view of a table with the gauge applied;

Fig. 3 is a similar front elevation, but showing the adjacent upper parts of the machine and the collar in section; and

Fig. 4 is a view similar to Fig. 2, but of the opposite side of the table and gauge attached thereto.

Referring to the drawings in detail, and especially Fig. 1, there is shown a conventional thong stitch sewing machine of which A is the frame, and B the driving pulley

fixed to the drive shaft suitably journaled in the frame. C represents the upper and lower take-up mechanism, including semi-circular thong guides with thong drawing or take-up arms D rotatably mounted on the guides C, and E designates the upper and lower needle bars adapted to grip the needle F carrying the thong G. The arms D are differentially rotated in the usual or any preferred manner and have the usual thong grippers, while the needle bars are reciprocated in timed relation thereto. The awl H, carried by the reciprocating awl bar or carrier I, is actuated by suitable mechanism, to produce the stitch in the work W movable on the table T beneath the presser foot P.

The table T has a shield S, so that the top 10 of the table forms with the top 11 of the shield S, a shoulder 12 and a circular part 13 therebeneath adapted for housing the lower take-up mechanism, together with mechanism which grips the needle or leader by which the stitching by means of the thong is carried on. The presser foot P has the awl bar or carrier mounted at one side thereof and beveled as at 14 and 15, the cut-away corners preventing the carrier pushing the work, especially horse collars, out of position and accommodating very thick work, especially the throat portions of heavy collars, without interference with the sewing operation.

The gauge consists of a plate 16 detachably secured at 17 to the inclined face 18 of the table or bed of the machine, and has a portion of its upper edge directed horizontally at 19 over the table leaving the corner 20 recessed. A plate or sliding section 21 is slidably mounted on the plate 16 having slots 22 receiving screws 23 which are secured to the plate 16 and have large heads straddling the slots, to permit free sliding movement of the plate 21. The latter is normally held upward by a spring 24 having its upper end anchored to the plate 16 and its lower end connected to the lower end of plate 21 or an extension thereof, as shown. The upper end of the plate 21 has an overhanging part or arm 25 directed inwardly at right angles laterally over the table top 10, with an upturned end 26 and a forwardly and downwardly curved plate or guard 27 at the front, formed integral therewith or secured thereto.

Thong sewing or stitching has heretofore been carried on with much difficulty, especially in sewing the rim of a horse collar to the body thereof. It is customary to stitch around the plies of the body, designated at 28 in the drawings, to sew them together and then to stitch the edges of the rim 29 over the body portion in order that the parts will be held in proper alignment for stitching the same together with a thong. In doing

ing this, an awl 30 is brought downward to provide the necessary hole for receiving the needle or leader and thong anchored thereto. Difficulty has been experienced in getting and keeping the proper overlap. The novel gauge overcomes this objection, since with it, the part 25 is spaced above the table and accommodates the lower fold of the rim 29 therebeneath. The edge of the lower fold engages the edge of the horizontal gauge portion 19 as indicated at 31, and the plies of the body rest upon the horizontal arm 25 and engage the shoulder or upturned end 26 at their inner edges, to limit the overlap and serve as a guide for gauging the same. The top fold of the rim fits over the body 28.

With the parts arranged as indicated in Fig. 3 of the drawings, the proper overlap will be insured and the stitching of the rim to the collar will be facilitated. In fact, it is possible to eliminate the initial operation of stitching the parts together with a thread since the gauge maintains the overlap uniform. By reason of the plate 21 being held up by the spring 24, the space between the overhanging gauge part or arm 25 and the table top 10 will accommodate heavy thicknesses of material and still allow the necessary downward movement to prevent injury or bending of the gauge parts and to bring the plies of material together so that they will be firmly brought in contact when stitched by the thong. While the device is described for use in connection with horse-collars, it is not restricted to this use but as a special adjunct, the awl carrier or bar I is provided with beveled or cutaway corners as indicated at 14 and 15 to accommodate a considerable thickness of material which is generally present at the throat portion of the collar. It should also be noted that the lower fold of the rim 29 is prevented from riding up over the gauge portion 19 by the inner edge 33 of the curved depending front portion 27, this feature serving to further maintain the overlap and stitching uniform. By this device, the rim and body can be stitched together by the thong without preliminary stitching, thus greatly increasing quantity production and reducing cost of manufacture.

It is believed that the foregoing conveys a clear understanding of the objects prefaced above and while I have illustrated but a single working embodiment it should be understood that changes might be made in details of construction without departing from the spirit and scope of the invention as expressed in the appended claims, in which—

I claim:

1. In combination with a thong sewing machine comprising a table, and an awl carrier provided with an awl, a gauge com-

- prising a plate attached to the table at one side and having a horizontal portion extending over the table to provide a shoulder facing in one direction, and an overhanging part spaced above the table and above said horizontal portion and provided with an upturned end forming an oppositely facing shoulder, and a downwardly and forwardly extending part forming a shoulder facing in the same direction as the first shoulder.
2. In combination with a thong sewing machine comprising a table, and an awl carrier provided with an awl, a gauge comprising a plate attached to the table at one side and having a horizontal portion extending over the table to provide a shoulder facing in one direction, and an overhanging part spaced above the table and above said horizontal portion and provided with an upturned end forming an oppositely facing shoulder, and a downwardly and forwardly extending part forming a shoulder facing in the same direction as the first shoulder, said overhanging part having a portion thereof slidably mounted on the plate at one side of the table for vertical movement, and means to normally maintain said horizontal portion elevated and adapted to permit the same to be depressed.
3. In a gauge attachment of the class described, a main attaching part having a horizontal portion forming a shoulder facing in one direction, a second part carried by the attaching part and having an overhanging portion extending above and beyond the horizontal portion, the latter providing a shoulder at its free end facing in the opposite direction from the first shoulder, and a forwardly and downwardly curved portion provided on said second named part and having its inner edge facing in the same direction as the first shoulder and substantially in alignment therewith.
4. A gauge for thong sewing machines having a table with a front shoulder and a sloping side, a main plate attached to the side and having a cut out forward corner and a horizontal head part extending partly over the table, a second plate mounted on the main plate and having an overhanging part extending over and spaced above the table beyond the horizontal part, said over-
- hanging part having an upturned free end and a forwardly and downwardly extending portion, the inner edge of which is adapted to guide the edge of the lower fold of a collar rim in conjunction with the inner edge of the horizontal part while the collar rim is resting on the table and has the upper fold thereof above the upturned end of said overhanging part, said overhanging part also being arranged to have plies of a collar body rest thereon against the upturned end thereof to maintain the same in uniform overlapped relation with said collar rim while being sewed.
5. In a sewing machine comprising a table, a presser foot operating over said table, and a needle operating mechanism, a gauge comprising a main plate fixed to said table and providing a shoulder on top of said table facing in one direction to gauge and guide the edge of one piece of material to be sewed, and a second plate movably mounted with respect to said main plate and having a gauging and guiding portion projecting over said table providing a shoulder facing in the opposite direction from the first shoulder to gauge and guide the edge of another piece or pieces of material to be sewed to the first piece, said gauging and guiding portion being normally resiliently held in elevated relation relative to said table to permit the passage therebeneath of the first mentioned piece of material to be sewed but being disposed beneath and in spaced relation to said presser foot whereby to permit the guiding of a fold of the first mentioned piece of material between the presser foot and the second mentioned piece of material, said guiding and gauging portion of said second named plate being arranged to be depressed in the operation of the presser foot substantially as described.
6. In a sewing machine as set forth in claim 5, the provision of an auxiliary gauging and guiding part for the first mentioned piece of material to be sewed, disposed substantially in alignment with the first named shoulder but spaced with respect thereto substantially as described.

HENRY B. OLSON.
